SIGNALING SYSTEM FOR RAILROADS

Sedgwick N. Wight, Rochester, N. Y., assignor to
General Railway Signal Company, Rochester,
N. Y.

Application August 30, 1929, Serial No. 389,446

17 Claims. (Cl. 246—3)

This invention relates to devices and systems for protecting train movements over power operated switches, and more particularly to means for locking such switches under predetermined conditions of traffic, and is an improvement over the systems shown in my prior applications Ser. No. 48,553 filed August 6, 1925 and Ser. No. 120,423 filed July 3, 1926.

Where track switches, operated by power under the control of an operator, are employed, it is important that suitable provision be made to prevent the operator from carelessly or accidentally causing operation of the switch by power in front of an approaching train, at such times and under such conditions that otherwise the switch might be in mid-stroke or unlocked when the train starts to pass over it. If the track is provided with track circuits for a sufficient distance from the switch, such desired protection may be obtained by the application of some one of the well known schemes of track circuit controlled approach locking; but in some cases, as on a passing siding or branch track, or the like, such track circuits may not be available to indicate the presence of a train approaching the switch, so that the ordinary types of track circuit controlled approach locking are not adequate to protect the movement of a train from such a siding or branch track.

With these considerations in mind, in accordance with the present invention, it is proposed to employ a time element device, in combination with suitable control circuits and a stick relay or its equivalent, in such a way that, whenever the signal is cleared to advance traffic from the siding, branch track, or other portion of track adjacent the switch and not equipped with track circuits, the switch can not thereafter be operated by power, even though this signal is afterwards caused to indicate stop, until after the lapse of predetermined time after a signal has been put to stop, sufficient to permit an approaching train either to come to a stop at the signal, or reach the point where the presence of the train prevents operation of the switch, due to the usual detector track circuit, or the like.

The characteristic features and advantages of the invention will be in part apparent to those skilled in the art, and in part pointed out, as the description progresses.

The accompanying drawing shows in a simplified and diagrammatic manner one specific embodiment of the invention, applied to an electrically operated switch at the end of a passing siding, the various parts and circuits involved in

the invention being shown more with the object of facilitating explanation and understanding of the nature of the invention, than with the purpose of illustrating in detail the structure and arrangement of parts and circuits preferably employed in practice.

Referring to the accompanying drawing, one end of a passing siding PS has been shown, with a track switch SW. The main track, and the portion of the siding up to the "fouling point" are provided with insulated joints and cross bonding, in accordance with common practice, to form a detector track circuit DTC, having a track relay T. The points of the switch SW are locked and operated by a suitable power switch machine SM, which is assumed to be of the well known electrically operated type, such as disclosed, for example, in the patent to W. K. Howe, No. 1,466,903, dated September 4, 1923. It is assumed that the operation of this switch machine SM to its normal and reverse positions from a local source of current, as a battery 5, is controlled by an operator at a distant point, by means of a suitable remote control relay, such as a neutral polar relay Z, which may be energized with current of one or the other polarity, or de-energized, over line wires 6 and 7, from a distant battery 8, in accordance with the position of a manually operable pole-changing switch 9. The switch machine SM, however, may be operated or controlled in any other suitable way, without departing from the invention.

In the specific embodiment of the invention shown, the operation of the switch machine SM is prevented, as and when desired, by directly controlling the supply of current from the battery 5 to the switch machine motor, although other expedients, well known in the art, may be employed for this same purpose. As shown, the connection from the battery 5 to the switch machine SM includes the front contact 10 of the detector track relay T, and the front contact 11 of a lock relay LR, so that no power can be supplied to the switch machine, irrespective of the position of the control relay Z, if the detector track circuit DTC is occupied, or if the lock relay LR is de-energized.

Signals 12 and 13 govern traffic toward the siding; signal 14 governs traffic on the main track; and signal 15, assumed to be a "dwarf" signal, governs traffic from the siding, all in accordance with common practice. These signals 12-15 have been illustrated as semaphore signals, but trackway signals of any suitable type may be employed, such as color light signals. In accordance

with this invention, these signals 12 to 15 are provided with suitable circuit controllers 16, 17, 18 and 19, respectively, which are closed only if the corresponding signal is in its stop position. If 5 color light signals are employed, suitable contacts on their control relays, or equivalent means, would be employed instead of such circuit controllers. The dwarf signal 15 is also provided with a circuit controller 20, closed when this signal indicates stop.

These several signals 12-15 are governed in accordance with the position of the switch SW, the presence or absence of trains in advance of the respective signals, and under the control of the 15 operator, in some suitable way in accordance with common practice. For example, these signals may be controlled by separate levers, or may be remotely controlled, in accordance with the principles of the dispatching system disclosed, for example, in my prior application, Ser. No. 48,553, filed August 6, 1925. Any suitable method of control of these signals, including the block signal circuits, may be employed in accordance with the invention.

25 The invention contemplates a suitable time element device TE, and a stick relay S, or equivalent means. This time element device TE may be of any suitable construction, operable electrically to close contacts after the lapse of a predetermined time, such as 20 seconds. As shown diagrammatically, this time element device is of the thermal element type, such as disclosed more in detail in my prior application Ser. No. 292,884, dated July 14, 1928, now matured into Patent No. 35 1,856,045, granted April 26, 1922, and comprises two thermal bi-metallic contact fingers 21 and 22, normally open, and adapted to be closed, after the lapse of a predetermined time, following the supply of heating current to a coil 23 on the finger 22.

40 For simplicity in illustration, the control circuits for the relays LR and S, and the thermal time element device TE, have been shown conventionally with the symbols (+) and (-) indicating the opposite terminals of a suitable battery, or other source of current.

Operation.—The stick relay S is normally energized, assuming that the dwarf signal 15 has not been cleared since the last movement of a train 50 over the switch, by a circuit which may be traced as follows: starting at (+), circuit controller 20 of signal 15, wires 25 and 26, coil 23 of time element device TE, wire 27, front contact 28 of relay S, wires 29 and 30, relay S, to (-). On account 55 of the resistance of the relay S in this circuit, the current in the coil 23 is not sufficient to heat the thermal finger 22.

With the stick relay S energized, and all of the signals 12-15 in the stop position, and assuming no train approaching the switch from either 60 direction on the main track, the lock relay LR is energized by a circuit which may be traced as follows:—starting at (+), front contact 31 of relay S, wire 32, circuit controller 18 of signal 14, wire 33, circuit controller 19 of signal 15, wire 34, 65 circuit controller 16 of signal 12, wire 35, circuit controller 17 of signal 13, wire 36, contact a, wire 37, relay LR, to (-). The contact a in this circuit and its controlling relay b represent grammatically such contact or contacts as are 70 necessary to provide approach locking protection for the switch SW for trains approaching on the main track in either direction. Such approach locking circuits, although some suitable form is 75 preferably employed in the practical application

of the invention, are not material to the invention, and may be of any suitable type, such as disclosed, for example, in my prior application, Ser. No. 48,553, filed August 6, 1925.

Under the conditions assumed, that is, with the 5 signals 12-15 all indicating stop, and no train approaching from either direction on the main track, and with the lock relay LR energized, the switch machine SM may be supplied with current to operate the switch points to either position, 10 dependent upon the position of the manually operable switch 9 and energization of the remote control relay Z.

Considering now the train movement, to which this invention more particularly relates, 15 assume that the operator, having caused the switch SW to assume the reverse position, and having cleared the dwarf signal 15, with the idea of permitting a train to move from the passing siding PS onto the main track, should for some 20 reason change his mind, and cause the signal 15 to assume the stop position; or, perhaps, the manipulation clearing the signal 15 was made accidentally or thoughtlessly, and is then 25 changed. Under these conditions, if there should happen to be a train on the passing siding PS approaching the signal 15, and if the engineman observing this signal in the clear position, should maintain or increase speed, this 30 train might not be able to stop, when the signal 15 was placed in the stop position; and unless some special provisions were made to prevent 35 operation of the switch machine, other than merely the fact that the signal 15 is in the stop position, the switch machine might be operating 40 at the time the train in question entered the detector track circuit DTC, with the result that the train might reach the switch points when unlocked or in mid-stroke. This would be true if the entrance of the train into the detector track 45 circuit DTC should at once cut off the power for operating the switch machine, as in the arrangement shown, or if provisions were made, as shown, for example, in the patent to W. K. Howe No. 1,399,257, dated December 6, 1921, to 50 permit the switch machine to complete the cycle of operation that had been started. Although such a train movement would trail through the switch points, and might not derail the train, the possible injury to the switch points or switch 55 operating mechanism makes it desirable to avoid such a contingency. Also, under the conditions assumed, the switch machine may be operated to its normal position, and under certain circumstances the signals 12 or 14 cleared, with the possibility that conflicting train movements on the main track might occur under conditions that might be unsafe with a train coming off of the siding.

60 This invention prevents operation of the switch under the conditions assumed. When the dwarf signal 15 is cleared, its circuit controller 20 opens and de-energizes the stick relay S, thereby breaking at its front contact 31 the energizing circuit for the lock relay LR, so as to prevent application of power to the switch machine SM. When the signal 15 is caused to assume its stop position by the operator, as in the case assumed, the stick relay S and the lock relay LR remain de-energized; and the switch machine SM cannot again be operated until the relay S is again picked up.

65 When the signal 15 is put back in its stop position, closing its circuit controller 20, the coil 70 23 of the time element device TE is supplied with 75

current through a circuit from (+), circuit controller 20, wires 25 and 26, coil 23, wire 27 and back contact 28 of relay S, to (-). This circuit for the coil 23 does not include the relay S; and this current in the coil 23 is sufficient to heat the thermal element constituting the finger 22 and cause this finger to contact with the other finger 21, after a time interval, thereby establishing a pick-up circuit for the relay S from (+), circuit controller 20, wires 25 and 26, fingers 22-21, wires 38, 39, and 30, relay S to (-). When the relay S is thus re-energized, it breaks at its back contact 28 the heating circuit for the coil 23, which then cools, opening the contacts 21-22, ready for the next operation.

The time element device TE is so designed and adjusted that, before the contact fingers 21-22 engage each other, a predetermined time, such as 20 seconds must elapse. This time interval is selected such that a train on the passing siding PS, approaching the signal 15, will either have time to stop, after the signal 15 has been put in the stop position, or if unable to stop, will run by the signal 15 into the detector track circuit DTC. When the train reaches the detector track circuit, the dropping of the track relay T prevents the operation of the switch machine SM, independently of the control of the relay LR, so that, if the approaching train is unable to stop and runs by the signal 15, the switch can not be operated by power until the train has advanced or backed up clear of this detector track circuit. It will be evident that this time interval should take into consideration the speed of trains on the passing siding PS, the sighting distance of the signal 15, and the braking distance of such trains; and any desired time interval may be employed, as found best adapted to particular operating conditions.

In the case of a normal movement of a train from the passing siding PS, the stick relay S is at once re-energized, without the time interval delay, because the signal 15 automatically assumes the stop position, upon movement of the train thereby, due to the usual track circuit control of this signal (not shown), and with the track relay T de-energized, a pick-up circuit for the stick relay S is established from (+), circuit controller 20, wires 25 and 40, back contact 41 of the track relay T, wires 39 and 30, relay S to (-). Thus, in the case of a normal train movement off of a siding, as soon as the train has cleared the detector track circuit DTC, the switch may be operated, without waiting for the time element device TE to close its contacts 21-22. This not only saves unnecessary delay in many instances, but also avoids the unnecessary operation of the time element device TE.

From the foregoing, it can be seen that there is provided by this invention a simple and efficient means for affording the necessary approach locking control of a switch for train movements from passing sidings, branch tracks, or similar stretches of track, which are not equipped with track circuits. It will be evident that the principles and essential features of the invention may be applied to varying conditions encountered in practice, and it should be understood that the invention is not limited to the particular construction and arrangement of parts shown and described.

What I claim is:—

1. In a system of the type described, the combination with a power operated track switch and a signal governing traffic over the switch, of a stick

relay controlling the application of power to the switch, a stick circuit for said relay broken when said signal indicates clear, a pick-up circuit for said relay, a thermally actuated time responsive device which when in its active condition closes said pick-up circuit, and an energizing circuit for rendering said time responsive device active closed only if said stick relay is deenergized and said signal indicates stop. 5

2. A system of the character described comprising, in combination with a power operated track switch and a signal governing traffic over the switch, of a relay acting while de-energized to prevent operation of the switch, and an energizing circuit for said relay including the contacts of a 15 thermal element time responsive device, said thermal element of said device being heated when said relay is deenergized and said signal indicates stop.

3. A system for protecting a train moving over power operated switches comprising, a stick relay governing the operation of the switch, a thermal time-responsive device for governing said relay and effective only if said siding signal is at stop, a main track signal associated with said switch, a siding signal associated with said switch, a detector track relay for controlling the energization of said stick relay independently of said thermal device, a lock relay which if deenergized prevents the operation of said switch, and a circuit for said lock relay including a front contact of said stick relay and a contact closed only if said main signal is at stop. 25

4. In combination, a track switch, a signal for governing traffic over said track switch, a lock relay which if deenergized prevents operation of said track switch, a stick relay having a front contact in the energizing circuit of said lock relay, a thermal relay, a pick-up circuit for said stick relay including a front contact of said thermal relay, and a circuit for the heating coil of said thermal relay including a contact closed when said signal is at stop. 30

5. In combination, a track switch, a signal for governing traffic over said track switch, a lock relay which if deenergized prevents operation of said track switch, a stick relay having a front contact in the energizing circuit of said lock relay, a thermal relay, a pick-up circuit for said stick relay including a front contact of said thermal relay; and a circuit for the heating coil of said thermal relay including a contact closed when said signal is at stop and including a back contact of said stick relay. 40

6. In combination, a track switch, a signal for governing traffic over said track switch, a lock relay which if deenergized prevents operation of said track switch, a stick relay having a front contact in the energizing circuit of said lock relay, a thermal relay, a pick-up circuit for said stick relay including a front contact of said thermal relay, a circuit for the heating coil of said thermal relay including a contact closed when said signal is at stop, and a contact open when there is a train approaching said switch included in the energizing circuit of said lock relay. 50

7. In combination, a track switch, a signal for governing traffic over said track switch, a lock relay which if deenergized prevents operation of said track switch, a stick relay having a front contact in the energizing circuit of said lock relay, a thermal relay, a pick-up circuit for said stick relay including a front contact of said thermal relay, a circuit for the heating coil of said thermal relay including a contact closed when 70

75 signal governing traffic over the switch, of a stick 75

- said signal is at stop and including a back contact of said stick relay, and a contact open when there is a train approaching said switch included in the energizing circuit of said lock relay.
- 5 8. In combination, a stick relay for at times preventing the movement of switch points of a railway track switch, a thermal relay having a normally open contact, an energizing circuit for said thermal relay including a contact closed only 5 when a signal associated with said track switch is at stop and a contact closed when said stick relay assumes its deenergized condition, and a pick-up circuit for said stick relay including said contact of said thermal relay.
- 10 9. In combination, a stick lock relay for at times preventing the movement of switch points of a railway track switch, a thermal relay having a normally open contact, an energizing circuit for said thermal relay including a contact closed only 10 when a signal associated with said track switch is at stop, a pick-up circuit for said lock relay including said contact of said thermal relay, and a stick circuit for said lock relay closed only if 15 said signal is at stop.
- 15 10. In combination, a lock stick relay for at times preventing the movement of switch points of a railway track switch, a thermal relay having a normally open contact, an energizing circuit for said thermal relay including a contact closed only 20 when a signal associated with said track switch is at stop, a pick-up circuit for said stick lock relay controlled by a contact of said thermal relay, and a stick circuit for said lock relay including a contact open when said signal is cleared.
- 25 11. In combination, a track switch of a railway system, a power operated switch machine for operating said track switch, a signal for governing movement of traffic over said track switch, a stick relay for at times preventing operation of said 25 switch machine and having a stick circuit closed only if said signal is at stop, a thermal relay having a contact open when in its deenergized cool condition, an energizing circuit for said thermal relay including a contact closed only when said 30 signal is at stop, and a pick-up circuit for said stick relay including said contact of said thermal relay.
- 35 12. In combination, a track switch of a railway system, a power operated switch machine for operating said track switch, a signal for governing movement of traffic over said track switch, a lock stick relay for at times preventing operation of said switch machine and having a stick circuit closed only if said signal is at 40 stop, a thermal relay having a contact open when in its deenergized cool condition, an energizing circuit for said thermal relay including a contact closed only when said signal is at stop, and a pick-up circuit for said lock relay including said contact of said thermal relay.
- 45 13. In combination, a track switch of a railway system, a power operated switch machine for operating said track switch, a signal for governing movement of traffic over said track switch, a lock stick relay for at times preventing operation of said switch machine, a thermal relay having a contact open when in its deenergized cool condition, an energizing circuit for said thermal relay including a contact closed 50 only if said signal is at stop, a pick-up circuit for said stick relay controlled by a contact of said thermal relay, and a stick circuit for said stick relay including a contact open when there is a train approaching said track switch.
- 55 14. In combination, a track switch, a signal for governing traffic over said track switch, a lock relay which if deenergized prevents operation of said track switch, a stick relay having a front contact in the energizing circuit of said lock relay, an approach relay having a contact 55 opened when there is a train approaching included in the energizing circuit of said lock relay, a thermal relay, a pick-up circuit for said stick relay including a front contact of said thermal relay, and a circuit for the heating coil of said thermal relay including a contact closed when said signal is at stop.
- 60 15. In combination, a lock stick relay for at times preventing the movement of switch points of a railway track switch, a thermal relay having a normally open contact, an energizing circuit for said thermal relay including a contact closed only when a signal associated with said track switch is at stop, a pick-up circuit for said lock relay including said contact of said thermal relay, a second pick-up circuit for said stick relay including a back contact of a detector track relay associated with said track switch, and a stick circuit for said lock relay closed only if said signal is at stop.
- 65 16. In combination, a track switch capable of setting up a main and a diverging route, a main signal governing traffic over said main route, a diverging route signal for governing traffic over said diverging route, a lock relay for preventing operation of said track switch, a stick relay, a circuit for said lock relay including a front contact of said stick relay and a contact closed only if said main signal is at stop, a pick-up circuit for said stick relay, thermal relay means 40 for closing said pick-up circuit a predetermined time after said diverging route signal has been put to stop, and a stick circuit for said stick relay broken if said diverging route signal is cleared.
- 70 17. A system for protecting trains moving over power-operated track switches comprising, a stick relay which must be energized to permit power operation of a track switch, a signal for governing the movement of traffic over said track switch, an electrically controlled thermal relay the energizing circuit of which may be closed only if said stick relay is deenergized and said signal is at stop and having a contact closed only if said thermal relay has been energized 45 for a predetermined period of time, a pick-up circuit for said stick relay including said contact, a second pick-up circuit for said stick relay including a back contact of a detector track relay associated with said track switch, and a stick circuit for said stick relay including a contact closed only if said signal is at stop.
